(57) **CLAIM**

The ornamental design for a liquid applicator, as shown and described.

DESCRIPTION

FIG. 1 is a front perspective view of a liquid applicator, showing the new design.

FIG. 2 is a left side elevational view thereof, the right side elevational view being a mirror image of the left side elevational view;

FIG. 3 is a top plan view thereof;

FIG. 4 is a bottom plan view thereof;

FIG. 5 is a front elevational view thereof; and,

FIG. 6 is a rear elevational view thereof.

The dash dot dash lines illustrate boundaries of the claimed design. The broken lines illustrate portions of the liquid applicator that form no part of the claimed design.

In addition, the surface shading illustrated in the drawings is provided merely to highlight contour of the design; it is not intended to be illustrative of texture or gloss.
